UNITED STATES PATENT OFFICE.

EMIL GATHMANN, OF WASHINGTON, DISTRICT OF COLUMBIA.

GUN.

SPECIFICATION forming part of Letters Patent No. 678,557, dated July 18, 1901.

Original application filed March 16, 1899, Serial No. 709,279. Divided and this application filed November 3, 1900. Serial No. 36,387. (No model.)

To all whom it may concern:

Be it known that I, EMIL GATHMANN, of Washington, in the District of Columbia, have invented certain new and useful Improvements 5 in Guns, of which the following is a specification.

This invention relates to improvements in rifled breech-loading guns, and refers more specifically to that class of ordnance adapted 10 for throwing large masses of high explosives in shells or aerial torpedoes, the present application being filed as a division of application Serial No. 709,279, filed March 16, 1899.

The invention has for its object to provide 15 a novel construction in the bore of a gun of the character referred to, whereby the shell charge will be subjected to a thorough setback by the expelling charge before the torpedo or shell is influenced or acted upon by 20 the rifling of the gun, thereby insuring corotation of the shell-body and its contents or charge.

The invention also has in view the production of a construction which will insure a 25 gradual and easy entrance of the rifling lands or ribs into the rotation-bands of the projectile, thereby insuring a uniform and low chamber-pressure with relatively high initial densities of loading. The construction further 30 provides for an intimate and complete contact of the rotation-bands of the projectile with the walls or bore of the gun, thereby preventing erosion and wash, which are mainly due to the passage of the propelling powder- 35 gases between the walls or bore and the rotation-bands.

To these ends my invention consists in certain novel features of construction, which I will now describe and will then more particularly point out and specify in the appended 40 claims.

In the accompanying drawings, Figure 1 is an axial sectional view of a gun embodying my invention, the rear end portion thereof 45 being broken off to reduce the size of the figure. Fig. 2 is a fragmentary sectional view of a portion of the gun, on a larger scale, and showing a portion of a projectile in elevation arranged therein. Fig. 3 is a view similar to 50 Fig. 2, on a still larger scale. Fig. 4 is a simi-

lar fragmentary view illustrating the relation of the shell to the bore when the same has advanced some distance along the bore of the gun. Fig. 5 is another similar view showing the projectile still further advanced along the 55 bore and in that portion of the latter when it is just entering the fully-rifled part thereof. Fig. 6 is a transverse fragmentary sectional view of the rifling of the gun, taken on line 66 of Fig. 1. Fig. 7 is a similar view taken on 60 line 77 of Fig. 1.

In breech-loading ordnance as now generally constructed the projectile is provided with a rotation-band, made of copper or the like, which is somewhat larger in diameter 65 than the bore of the gun, measured from the bottom of the rifling-grooves, the bore of the gun being ordinarily provided with rifling terminating quite abruptly at or near the forward end of the powder-chamber at what is 70 termed the "compression" or "forcing" slope. A relatively large amount of force is required to start or enter the band of a projectile into the rifling when the latter terminates in this abrupt or short slope, as has 75 hitherto been the usual case.

In practice it has been found, particularly with guns of large diameter of bore, that the abrupt termination of the rifling and consequent heavy forcing required to start or enter the projectile within the rifling causes irregular and high chamber-pressure, great erosion, and wear upon the rear portion of the bore of the gun, and when large masses of high explosives are carried in projectiles 85 undue measures of shock and friction are transmitted to the explosive by reason of this violent motion imparted to the projectile during the moment its band is being forced into the rifling. It is to obviate this and other 90 objections that I provide the construction shown in the accompanying drawings, in which—

10 indicates as a whole the body of a gun having at its rear end the usual powder or 95 charge chamber 11 and immediately in advance of this a short position-slope 12. Lying intermediate this position-slope 12 and the fully-rifled portion of the bore 13 is a conical shell-chamber 14, preferably and as 100

shown herein of uniform decreasing taper from the position-slope to that part of the chamber containing full-depth rifles.

The powder-chamber 11 may be of any approved construction, being, as usual, of greater diameter than the shell. The position-slope 12 connects the powder-chamber 11 and the shell-chamber 14 and consists of a short relatively abrupt inclined or conical shoulder, as indicated clearly in the drawings. The shell-chamber 14 is of gradually decreasing diameter from the position-slope toward the rifling, as shown clearly in the several figures of the drawings, and merges gradually into the rifled portion of the bore at its forward end, being, however, of greater diameter than the body or shell at its forward and smaller end.

A projectile—such, for example, as that indicated at 15—provided with any suitable or desired compression rotation-band, as indicated at 16, constructed of copper or analogous material, is inserted in the chamber and pushed forward until its band 16 engages the position-slope 12 and its bourrelet 17 has entered the cylindrical fully-rifled portion 13 of the bore of the gun.

18 designates the lands of the rifled portion of the gun, and 19 the grooves or rifles proper, these being shown in their normal width and depth in Fig. 7.

18, Fig. 6, designates the lands and rifle-grooves as they appear in cross-section, taken on line 66 of Fig. 1 or through the forward part of the shell-chamber, where the latter merges into the main cylindric bore of the gun, said figure being intended to bring out clearly the reduced heights of said lands in this part of the shell-chamber, the lands finally running out entirely at that point in the shell-chamber which is of the same diameter as the diameter of the main bore, including the depth of the rifle-grooves 19. A gun having a bore constructed as thus described when loaded with and firing a projectile provided with any suitable compression rotation, band—such, for example, as that described herein—operates substantially in the following manner: Upon the explosion of the propelling charge the projectile moves forward and the rotation-band of the same enters within the conical shell-chamber 14, and while moving forward through this part of the bore the taper or gradual decrease in diameter of the shell-chamber exercises a compressing action upon the rotation-band 16, which acts to gradually swage the same into position upon the lands of the rifling of the bore of the gun substantially in the manner indicated in the series of progressive positions indicated by Figs. 3, 4, and 5.

In Fig. 4 of the drawings the shell is shown in the condition in which it exists when the compression or rotation band has passed partly through the shell-chamber, and it is to be observed that the body of the band then presses tightly against the walls of the cham-

ber, forming an effectual gas-check to arrest the flow of propelling-gases past the band. As the projectile travels forwardly the fit of the band within the chamber becomes tighter and tighter and the friction consequently greater, but the projectile meanwhile gains energy from its own momentum as well as from the increasing pressure of the propelling-gases, so that when the rotation-band finally enters the fully-rifled section of the bore, as shown in Fig. 5, it does not occasion any sudden jar or strain to either gun or projectile, as is the case with guns as heretofore usually constructed having the abrupt entrance from the shell-chamber to the rifling.

As before stated, the gradually tapering or decreasing diameter of the shell-chamber exercises a compressing or swaging action on the rotation-band of the projectile and avoids the cutting or planing effect produced by the usual form of bore wherein the projectile enters abruptly to the rifling.

A special form of rotation-band such as described in my United States application, Serial No. 709,279, may be advantageously used in guns constructed with a shell-chamber of the type herein described, but any other form of suitable compression-banded projectile may obviously be used if the band be made of suitable diameter.

By the compressing and swaging action of the tapered shell-chamber upon the rotation-band of the projectile a very perfect gas-check is insured immediately upon the entrance of the band to this chamber and the destructive wash and erosive actions due to the highly-heated powder-gases passing the projectile while within the bore of the gun are thereby obviated.

This construction of gun is particularly applicable for firing shells or aerial torpedoes containing large masses of high explosives, such as wet guncotton and the like. It will be seen that as the first or initial movement of the projectile when being fired from the gun is entirely and only a direct forward movement, a thorough set-back is imparted to the shell charge before the rifled portion of the gun is entered, thus insuring a corotation of the charge of the shell with the latter when rotary motion is imparted by the rifling. The tapered shell-chamber also reduces the power necessary to overcome the combined inertia of the projectile and frictional resistance of the bore thereon for the reason that the forcing required to enter the rotation-bands within the rifling is much less than with other systems or constructions. More uniform and relatively lower chamber-pressures are therefore insured than obtain with the usual form of rifling start and bore, thus allowing guns having relatively lighter walls to be employed for a given muzzle energy.

It will be obvious that modifications may be made in the details of rifling, in the length of and taper of the shell-chamber, and otherwise without departing from the spirit of the

invention, and I do not therefore wish to be limited to the precise construction hereinbefore described, and shown in the drawings, except as the same may be made the subject of 5 specific claims.

I claim as my invention—

1. In a gun, the combination of a charge-chamber, a main bore of substantially less diameter than the charge-chamber, and a projectile-chamber intervening between the charge-chamber and main bore, of forwardly-tapered form.
2. In a gun, the combination of a charge-chamber, a main bore of substantially less diameter than the charge-chamber, and a projectile-chamber between the charge-chamber and main bore, having uniformly-tapered sides which merge into the main bore at the forward end of said chamber.
3. In a gun, the combination of a charge-chamber, a main bore of substantially less diameter than the charge-chamber and provided with rifling, and a projectile-chamber between the charge-chamber and main bore 25 having a gradually-diminishing diameter from its rear end forwardly and merging into the main bore at its forward end.

4. In a gun, the combination of a charge-chamber, a main bore of substantially less diameter than the charge-chamber, and provided with rifling, a projectile-chamber between the charge-chamber and the main bore, of gradually-diminishing diameter from its rear end forwardly and merging into the main bore at its forward end, and a relatively abrupt position-slope between the charge-chamber and projectile-chamber, substantially as described. 30

5. In a gun, the combination of a charge-chamber, a main bore of substantially less diameter than the charge-chamber and a projectile-chamber between the charge-chamber and main bore, of uniformly-decreasing diameter from its rear end forwardly and merging into the main bore at its forward end, 40 said main bore being provided with rifling continued back into the forward portion of said projectile-chamber until it vanishes in the tapered sides of the latter, substantially as described. 45

EMIL GATHMANN.
